UNITED STATES PATENT OFFICE.

IVER JOHNSON AND ANDREW FYRBERG, OF WORCESTER, MASSACHUSETTS;
SAID FYRBERG ASSIGNOR TO SAID JOHNSON.

VELOCIPED.

SPECIFICATION forming part of Letters Patent No. 388,048, dated August 21, 1888.

Application filed December 29, 1887. Serial No. 259,291. (No model.)

To all whom it may concern:

Be it known that we, IVER JOHNSON and ANDREW FYRBERG, both of Worcester, in the county of Worcester and State of Massachusetts, have invented certain new and useful Improvements in Velocipedes; and we do hereby declare that the following is a full, clear, and exact description of the same, reference being had to the accompanying drawings, forming a part of this specification, and in which—

Figures 1, 2, and 3 represent a plan view, front view, and side view, respectively, of so much of a bicycle as is necessary to illustrate our improvements. All the following figures are upon an enlarged scale. Fig. 4 is a vertical longitudinal section on line *a*, Fig. 1, through the inner end of one of the foot-treadles and upper end of its supporting crank-arm. Fig. 5 is a similar section on line *b* of the outer end of one of the foot-treadles. Fig. 6 is a cross or transverse section on line *c* through said foot-treadle. Fig. 7 is a cross or transverse section on line *d* through the treadle-bolt, looking toward the inner end of the treadle. Fig. 8 is a similar section on line *e* through said inner end of the treadle and its bolt, showing a modification in the construction, hereinafter described. Figs. 9 and 10 are a detached front and edge view, respectively, of a flanged plate interposed between the crank-arm and foot-treadle, as and for the purpose also hereinafter described. Fig. 11 is an end view of the crank-arm bearing, looking in the direction of arrow *f*, Fig. 2, with the nut removed to more fully illustrate our improvement thereon. Fig. 12 is a detached side view of our improved lock-washer, hereinafter described. Fig. 13 is a vertical longitudinal section on line *g*, Fig. 11, through that portion of the crank-lever bearing to which our improvements relate. Fig. 14 is a similar section showing a modification in the construction of said lever-bearing, hereinafter described; and Fig. 15 is a side view of our aforesaid improved lock-washer, showing a modification in its construction, also hereinafter described.

Our invention is more especially designed for bicycles, but is also applicable to other forms of vehicles; and it consists of improvements upon the foot-treadle crank-bearings, as hereinafter more fully set forth.

In order that others may fully understand the nature and purpose of our said improvements, we will now proceed to describe the same in detail in connection with such old parts of a bicycle as are combined and coact therewith.

In the drawings, the part A represents one of the usual crank-arms for imparting power to the driving-wheels of the bicycle, B the hub or bearing thereof, and C the foot-treadle mounted on the upper end of said crank-arm.

Our improvements upon the bicycle are mainly upon the treadle construction, the improvement upon the crank-arm bearing being simply a duplication of one part of the treadle improvements with slight changes therein to adapt the same to said different application, as hereinafter specified.

Said improvements consist of means for imparting a rotary spring motion to the treadle to bring it back into its normal position after the foot-pressure is released therefrom, for controlling the rotary movements of the treadle, and for excluding dust around the inner end thereof; also, for locking its outer nut, washer, and bearing from rotary and longitudinal movement upon the central bolt, and for securing the usual foot cushions or pads in position. The aforesaid rotary back-spring motion is imparted to the treadle by means of a suitable spring, *h*, disposed in this instance within a circular peripheral groove, *i*, formed around the inner end of the usual central bolt, *j*, under the enlarged socketed end *k* of the central longitudinal treadle bearing or sleeve, *k*. Said spring is preferably arranged in the above position and made in the form of a spiral coiled around the bolt *j* and its two ends connected, respectively, with the sleeve *k* and said bolt *j*, as shown in Fig. 4. We do not limit ourselves, however, to the above arrangement and construction, as the same result may be effected in various other similar ways. An illustration of one other way is indicated in Fig. 8, which represents a coiled instead of a spiral spring over the central bolt, *j*.

By either of the above-described constructions it is obvious that in operating the bicycle when the treadle is rotated on its bearing, as indicated by dotted lines in Fig. 3, upon removing the foot, and thereby releasing the

pressure therefrom, it is immediately sprung back by the spring into its normal position. (Shown by full lines.) Therefore it is always in convenient position for the rider to apply his foot thereto.

The rotary movements of the treadle are controlled in both directions by the lateral projection or foot-guard k^2 thereof striking against the shoulder l or l' , as the case may be, 10 the shoulder l serving to stop and hold the treadle at the proper place when sprung back into its normal position by the spring h , as previously described, and the shoulder l' to control the opposite rotary motion of said 15 treadle, produced by the foot of the rider in operating the machine. The aforesaid shoulders project laterally from a plate or washer, m , interposed between the inner end of the treadle and the crank-arm A. In this instance said plate is made separate from the bolt, being provided with a central opening, m' , to receive said bolt, and with a radial slot, m^2 , in which a flange or key, m^3 , on the bolt fits to hold said plate from turning thereon. 20 The plate is also provided with a lateral circular flange, m^4 , which fits over the inner end of the treadle-sleeve k , and thus serves as a dust excluder or guard over said end, as well as the purpose previously described. The 25 shoulders l l' are preferably formed by extending a portion of said circular flange m^4 out longer, as shown at m^5 in Figs. 9 and 10; but, if desired, the plate or washer may be made without either of the aforesaid flanges m^4 or 30 m^5 , and the shoulders l l' produced by fastening pins laterally therein, or in any other similar manner. If preferred, the plate or washer m may be formed upon or integral with bolt j , instead of separately, and fastened in position 35 thereon, as previously specified.

Our improvement upon the outer end of the treadle C consists in interposing a lock-washer, n , between the usual lock-nut, o , and the bearing p , upon which the outer end of the treadle turns, said lock-washer being provided with a series of peripheral notches, t , and serving the purpose of locking the nut o and bearing p from rotary and longitudinal movement upon the central bolt, j , which result is effected by 45 forming a longitudinal slot or groove, q , in the outer end of said bolt j and an internal flange, r , on the lock-washer n , which fits into said slot q when the parts are fitted together. The washer is also locked to the bearing p by means 50 of a pin, s , or its equivalent, projecting longitudinally from the outer side of said bearing, which engages with one or another of said series of notches t , formed around the periphery of the washer, as shown in the drawings.

60 By the above construction it will be apparent that when the bearing p , washer n , and nut o are adjusted in position, as shown in Fig. 5, all of said parts are effectually locked in said position against any rotary or longitudinal movement upon the bolt j , the bearing and washer being locked positively in the manner above described and the nut by frictional con-

tact with said rigidly-locked washer. By said construction it is obvious that the nut cannot by any ordinary usage become loose and fall off, as is usually the case when a loose washer is employed between said nut and the bearing. 70

We reserve the right to use our aforesaid lock device on other parts of a bicycle, as well as in any other similar places to which it 75 is adapted.

In the drawings we have shown one other application thereof to the crank-arm bearing or hub B for a like purpose to that previously described, and the same letters of reference 80 are used to designate the several parts as in the former instance.

Although it is preferable to make the lock-washer with peripheral notches, as and for the purpose set forth, an equivalent result may be 85 obtained by forming a series of holes around said washer close to its periphery to receive the pin s , and we therefore do not limit ourselves to said notches. The foot-treadle pads are held in position in the foot-treadle frame 90 k by making said frame with the two longitudinal slots or grooves U U to receive the usual rubber pads, v v , and with the inwardly-turned flanges v' v' v' v' for holding said pads in position after being fitted in said grooves. 95

To admit of the above adjustment, the pads are provided with longitudinal side grooves, v^2 v^2 , corresponding in shape to the aforesaid flanges v' , as best shown in Figs. 3 and 6. In fitting the pads to the treadle they are slipped 100 endwise into their respective grooves U , and when thus fitted are securely held in position without the use of other fastenings, thus, as will be seen, producing a simple as well as effective means of fastening said pads to the 105 treadle.

We are aware of the United States reissue patent to P. Lallement for improvement in velocipedes, No. 7,972, dated November 27, 1877, which shows the foot-treadles provided 110 with counter-weights for accomplishing the same purpose as the spring h in our improved velocipede, and we therefore make no claim thereto, broadly.

Having described our invention, what we 115 claim as new, and desire to secure by Letters Patent, is—

1. In a velocipede, the combination of the rotatable foot-treadle frame thereof and the central pivot bolt or shaft upon which it turns 120 with a suitable spring, h , fitted over said shaft, attached at one end to the shaft and at its other end to the frame, and the plate or washer m , interposed between said treadle-frame and the crank-arm, and having the shoulders l l' , or 125 their equivalents, adapted to strike against the foot-guard k^2 , substantially as and for the purpose set forth.

2. The combination of the crank-arm A, treadle-bolt j , fastened to said arm and having 130 a peripheral groove at its inner end, foot-treadle C, made with the hollow sleeve k and having the laterally-projecting flange k^2 at the inner end thereof, spring h , disposed within

the aforesaid peripheral groove and having its ends connected, respectively, with said foot-treadle and bolt j , and plate m , having the shoulders l so arranged that the flange k^2 will come in contact therewith when the foot-treadle is rotated, substantially as and for the purpose set forth.

3. The combination of the crank-arm A, treadle-bolt j , fastened to said arm, provided with the key m^3 near the arm, and having the peripheral groove i at its inner end, foot-treadle C, made with the hollow sleeve k and having the lateral projecting flange k^2 at its inner end, spring h , disposed within the aforesaid peripheral groove around bolt j and having its ends connected, respectively, with the foot-treadle and said bolt, and plate m , arranged between the crank-arm and treadle, having the circular flange m^4 fitting over the end of the treadle-sleeve, also having the shoulders l , and so arranged that the flange k^2 will come in contact therewith when the treadle is rotated, substantially as and for the purposes set forth:

25 4. The combination of the crank-arm A, treadle-bolt j , provided with the key m^3 , and foot-treadle C, made with the central sleeve,

k , and having the lateral projection k^2 at its inner end, with the plate m , having the central opening, m' , radial slot m^3 , and lateral flange m^4 , and interposed between the crank-arm and treadle, substantially as and for the purposes set forth.

5. In a velocipede, a dust-guard interposed between the crank-arm and foot-treadle, consisting of a plate, m , formed upon or fastened to the treadle-bolt, and having a laterally-projecting rim or flange, m^4 , extending over the inner end of the treadle-sleeve, substantially as set forth.

6. The combination of the treadle C, bolt j , having the longitudinal slot q in its outer end, the usual lock-nut, o , and the bearing p , or its equivalent, having the longitudinal projection or pin s , with the washer n , having the internal flange, r , and peripheral notches t , or their equivalents, substantially as and for the purpose set forth.

IVER JOHNSON.
ANDREW FYRBERG.
